COMBINATION STORAGE AND CARRYING CASE

Marshall B. Johnson, Bel Air, Md., assignor to The Black and Decker Manufacturing Company, Towson, Md., a corporation of Maryland

Filed Nov. 29, 1963, Ser. No. 77,607

Term of patent 14 years

(Cl. D87—5)

FIG. 1

FIG. 5

FIG. 4

FIG. 3

FIGURE 1 is a front perspective view of a combination storage and carrying case embodying my new design;

FIG. 2 is a top plan view thereof on a reduced scale;

FIG. 3 is an elevational view of the end opposite that shown in FIG. 1;

FIG. 4 is an elevational view of the side opposite that shown in FIG. 1; and

FIG. 5 is an enlarged fragmentary cross-sectional view thereof taken on line 5—5 of FIG. 1.

I claim:

The ornamental design for a combination storage and carrying case, as shown.
